UNITED STATES PATENT OFFICE.

CORA SARAH REIBER, OF NEW YORK, N. Y., ASSIGNOR TO BAECK WALL PAPER COMPANY, OF BROOKLYN, NEW YORK, A CORPORATION OF NEW YORK.

DESIGN FOR WALL PAPER OR SIMILAR ARTICLE.

Application filed May 21, 1926. Serial No. 17,792. Term of patent 7 years.

To all whom it may concern:

Be it known that I, CORA SARAH REIBER, a citizen of the United States of America, residing at 1544 Shakespeare Avenue, Bronx Borough, city of New York, and State of New York, have invented a new, original, and ornamental Design for Wall Paper or Similar Article, of which the following is a specification, reference being had to the accompanying drawing, forming part thereof.

The figure is a plan view of wall paper showing my new design applied thereto.

I claim:

The ornamental design for wall paper or similar article as shown.

In testimony whereof I have signed my name to this specification.

CORA S. REIBER.
